COMBINED MICROPHONE AND LOUD-SPEAKER OR SIMILAR ARTICLE

Howard S. Taylor, Fox River Grove, Ill., assignor to
Airguide Instrument Company, Chicago, Ill., a corpora-
tion of Illinois

Filed May 23, 1960, Ser. No. 60,689

Term of patent 14 years

(Cl. D26—14)

Fig. 1 is a side elevational view of a combined microphone and loud-speaker or similar article showing my new design, the opposite side being substantially a mirror image thereof;

Fig. 2 is a front elevational view thereof;

Fig. 3 is a rear elevation view thereof; and

Fig. 4 is a top plan view, the bottom being substantially a mirror image thereof.

I claim:

The ornamental design for a combined microphone and loud-speaker or similar article, as shown and described.
